(Cl. D45—10)

Fig. 1

Fig. 2

Fig. 3

*Fig. 4**Fig. 5**Fig. 6*FIG. 1 is a front elevation of a finger ring embodying my new design wherein the transverse stone cramps terminate below the annular ring of the setting;

FIG. 2 is a view in side elevation thereof;

FIG. 3 is a top plan view thereof;

FIG. 4 is a front elevational view of the ring design shown in FIG. 1 wherein all of the stone cramps extend above the annular ring of the setting;

FIG. 5 is a side elevation thereof; and

FIG. 6 is a top plan view thereof.

This application is a continuation of my earlier filed

applications D. 61,073 and D. 61,074, filed June 22, 1960, both now abandoned.

I claim:

The ornamental design for a finger ring, substantially as shown and described.
